BERNARD H. KERSTING, OF BEN AVON, PENNSYLVANIA, ASSIGNOR TO THE DRAVO CONTRACTING COMPANY, OF PITTSBURGH, PENNSYLVANIA, A CORPORATION OF PENNSYLVANIA

RAIL CLAMP FOR TRAVELING BRIDGES

Application filed June 19, 1924. Serial No. 721,066.

The present invention relates to rail clamps for traveling bridges, a preferred embodiment of the invention being illustrated in the accompanying drawings, in which:

5 Figure 1 is a side elevation of a traveling bridge to which the invention is applied;

Figures 2 and 3 are sections on the lines II—II and III—III, respectively, of Figure 1, looking in the direction of the arrows;

10 Figure 4 is a view in elevation, on a larger scale, showing the rail clamp mechanism which is associated with each leg of the bridge;

Figure 5 is a broken plan view of the mechanism shown in Figure 4;

Figure 6 is an end view of the structure shown in Figures 4 and 5, looking from the right, showing the clamping levers of one of the rail clamps in closed position;

20 Figure 7 is a section on the line VII—VII of Figure 4 showing the clamping levers in open position;

Figure 8 is a detail view of a yoke member;

Figure 9 is a detail view of an equalizer pin;

Figure 10 is a detail view of a yoke pin, and

Figures 11, 12, 13 and 14 are wiring diagrams.

30 Referring to Figures 1, 2 and 3, the numeral 2 designates a traveling bridge having legs 3 and 4 carried on trucks 5 which move along the tracks 6. This bridge is provided with the usual clamshell bucket 7 and operator's cap 8. Associated with each truck is a rail clamp mechanism 9 embodying my invention.

As will be apparent by reference to Figures 4 and 5, each clamp mechanism comprises 40 two separate rail clamps 10 and 11 controlled by a single electric motor 12 mounted on the corresponding truck 5. The motor has a pinion 13 on its armature shaft meshing with a gear 14 carried on one end of a shaft 15 journaled in the truck. Carried on the other end of this shaft is a pinion 16 meshing with a gear 17 on one end of the drum shaft 18. Carried on the other end of this shaft is a drum 19 around which a cable 20 winds. The 45 cable passes around the sheaves 21 and 22 of

the clamp 10 and has its end 23 looped about a cable anchor 24 in the form of a grooved pulley carried by the pin 25 of the sheave 22. The pin 26 of the sheave 21 is carried in brackets 27.

55 The clamps 10 and 11 are exactly alike in construction and operation so that a detailed description of the clamp 10 will suffice, the parts of clamp 11 being designated by the same reference numerals as corresponding parts of the clamp 10.

The clamp 10 comprises a pair of rail clamp levers 28 and 29 bifurcated at their upper ends to straddle the sheaves 21 and 22 and pivoted upon the sheave pins 25 and 26. These levers carry

60 at their lower ends clamp jaws 30 adapted to grip the sides of the rail 6. The levers are connected adjacent their lower ends by links 31 which are pivotally connected thereto by the pivot bolts 32. These bolts extend

65 through slots 33 in reinforcing plates 34 and channels 35. The reinforcing plates and channels are rigidly connected at their ends in any appropriate manner to angles 36 secured to side plates 37 depending from the

70 truck 5. Secured to the lower ends of the plates 37 are angles 38 and 39 whose horizontal flanges extend inwardly towards the beveled edges 40 and 41 of the clamp levers 28 and 29. The angles 36, side plates 37, 75 reinforcing plates 34 and channels 35 constitute a rigid frame or housing for the clamp levers. It will be noted that there is a slight amount of clearance between the ends of the connecting links 31 and the sides of this

75 housing, for a purpose which will be explained hereinafter.

80 Pivoted upon the sheave pin 26 at the outer sides of the bifurcated upper end of the clamp lever 28 are bell cranks 42. Each bell crank is pivotally connected at one end to a screw clevise 43, the latter being adjustably connected to an eye-bolt 44. The eye-bolts are pivoted upon the sheave pin 25 at the outer sides of the upper bifurcated end of

85 the crank lever 29 and the adjustment between the eye-bolts and clevises is maintained by lock-nuts 45.

85 Pivoted upon the sheave pin 26 at the outer sides of the bifurcated upper end of the clamp lever 28 are bell cranks 42. Each bell crank is pivotally connected at one end to a screw clevise 43, the latter being adjustably connected to an eye-bolt 44. The eye-bolts are pivoted upon the sheave pin 25 at the outer sides of the upper bifurcated end of

90 the crank lever 29 and the adjustment between the eye-bolts and clevises is maintained by lock-nuts 45.

95 Pivoted upon the sheave pin 26 at the outer sides of the bifurcated upper end of the clamp lever 28 are bell cranks 42. Each bell crank is pivotally connected at one end to a screw clevise 43, the latter being adjustably connected to an eye-bolt 44. The eye-bolts are pivoted upon the sheave pin 25 at the outer sides of the upper bifurcated end of

95 the crank lever 29 and the adjustment between the eye-bolts and clevises is maintained by lock-nuts 45.

100 Pivoted upon the sheave pin 26 at the outer sides of the bifurcated upper end of the clamp lever 28 are bell cranks 42. Each bell crank is pivotally connected at one end to a screw clevise 43, the latter being adjustably connected to an eye-bolt 44. The eye-bolts are pivoted upon the sheave pin 25 at the outer sides of the upper bifurcated end of

105 the crank lever 29 and the adjustment between the eye-bolts and clevises is maintained by lock-nuts 45.

yoke is connected at its other end to an equalizer slidably mounted between guides 100. This equalizer consists of parallel plates 47 spaced apart by spacers 48. Journaled between said plates centrally thereof is an equalizer pin 49. This equalizer pin has a bore through which extends a yoke pin 50. The yoke pin has its ends fixed in the bifurcated extremity of the yoke. The bifurcated extremity of the yoke is rounded and there is a slight clearance between said rounded extremity and the plates 47. It will be apparent, therefore, that a substantially universal connection is provided between the equalizer and the yoke since the equalizer can rock about the journals of the equalizer pin 49 and the latter can rock on the yoke pin 50 which is at right angles to the axis of the equalizer pin.

20 Spring rods 51 are pivotally connected at one end to the ends of the equalizer. These rods are surrounded by helical springs 52 housed in a spring box 53 mounted on top of the truck 5. Each spring abuts at one end 25 against a plate 54, held on the free end of the corresponding spring rod by a nut 55, and at the other end against a fixed portion of the spring box. The spring rods 51 are each provided with nuts 51^a on that portion of the rod 51 projecting beyond the fixed portion of the frame against which the spring 52 abuts. These nuts act as positive stops for limiting the range of effective operation of the spring and they are of decided importance for two reasons. If the clamp jaw should happen to wear to a point where gripping could be effected only by undue expansion of the springs 52 the nut 51^a will bear against the spring box and the operator will 35 thus be warned that he must adjust the portions 43 and 44 of the toggle arm in order to take up the wear. A further advantage is that the nuts permit the disassembling of the connecting means between the rod 51 and the 40 clamp jaw proper without entirely releasing the spring from the initial load which is imposed thereon in order that the springs exert the desired closing force at the limit of their operating travel.

45 A cable 56 also winds on the drum 19 and extends therefrom over a sheave 57 mounted on the housing of the clamp 11 and then passes around the sheaves 21 and 22 of the latter clamp and has its end 58 looped around 50 a cable anchor 24 on the sheave pin 25. Associated with the sheave 57 is a cable guard 59.

55 When the drum 19 is rotated in a direction to wind the cables 20 and 56 thereon, the sheaves 22 of the clamps 10 and 11 are moved towards the sheaves 21, thereby rocking the clamping levers 29 on their pivots 32 to disengage their clamp jaws 30 from the rails. After the beveled edges 41 of said levers engage the edges of the horizontal flanges of

the angles 39, further rocking movement of the levers 29 takes place about the points of engagement of said beveled edges with said flanges and causes the clamping jaws of the levers 28 to be backed away from the rails through the links 31. This movement is permitted by reason of the clearance between the ends of the links 31 and the sides of the housings for the clamp levers and also by reason of the slots 33 in the reinforcing plates 34 and channels 35 through which the ends of the pivot bolts extend. The relative movement of the upper extremities of the clamp levers towards each other causes the toggles 42-43-44 to move from the position shown in Figure 6 to that shown in Figure 7, thereby rocking the bell cranks 42 in a clockwise direction and putting the springs 52 under tension. When the circuit of the motor 12 is opened these springs immediately move the clamp levers back into the position shown in Figure 6, in which the rail is gripped by the clamp jaws. During the closing of the clamps, the levers 29 are rocked about their pivots 32 until the clamp jaws 30 at the lower ends of the levers engage the rails. Thereafter, the clamp jaws 30 at the lower ends of the levers 28 are pulled into engagement with the rails through the links 31.

55 Associated with the clamp 10 of each clamp mechanism 9 is a pair of limit switches 61 and 62, as shown in the wiring diagrams of Figures 11, 12, 13 and 14. These switches are located in a housing 60 carried by supports 101 and are adapted to be operated in unison by a lever 63 in such manner that when one switch is closed the other is opened, and vice versa. The lever 63 is pivoted to the hatchway at 64 and has its outer extremity bifurcated, a roller 65 being journaled in this bifurcated extremity. The upper plate 47 of the corresponding equalizer has a beveled edge 66 for cooperation with this roller. In the closed position of the clamp 10, as illustrated in Figure 6, the equalizer is out of contact with the roller 65 and the limit switch 61 is closed and the limit switch 62 open, as shown in Figures 11 and 13. When the clamp has been moved to open position, however, the equalizer is in the advanced position shown in Figure 7, in which the roller 65 is held thereby in raised position. In this position of the parts, the switch 61 is open and the switch 62 is closed, as shown in Figure 12.

55 Figures 11, 12 and 13 are wiring diagrams of either motor 12, and Figure 14 is a combined wiring diagram of both motors. Referring to these wiring diagrams, the two motors 12 of the clamp mechanisms 9 for the two legs of the bridge are connected in parallel with the feed lines and are adapted to be controlled by a foot-operated switch 67 located in the operator's cab, said switch being normally open, as illustrated in Figure 120

13. When the operator desires to move the bridge, he closes the foot switch. This completes a circuit through the magnet coils 68 and 69 and causes the contact 70 to close and the contact 71 to open, as shown in Figure 5. 11. The closing of the contact 70 completes a circuit through the magnet coil 72, causing the contact 73 to close also. The closing of the contacts 70 and 73 closes the motor circuit through the resistances R' and R^2 . The 10 motors are then operated simultaneously to turn the drums 19 in a direction to wind the cables 20 and 56 thereon, thus opening the clamps. When the clamps have been moved to fully 15 open position, the limit switches 61 of the two clamp mechanisms are open and the limit switches 62 closed, as illustrated in Figure 20 12, by reason of the engagement of the equalizers of the clamps 10 with the rollers 63. The opening of the limit switch 61 of either motor 25 breaks the circuit of the contact 73 thereby causing said contact to open and cut the resistance R^3 into the motor circuit. This stops the motors 12 but passes sufficient current 30 through them to hold the clamps open against the tendency of the springs 52 to close them. It will be apparent, by reference to Figure 14, that since the limit switches 62 of the two 35 motors are connected in series in the circuit of the controller for the bridge traversing motor, the bridge cannot be moved until both clamp mechanisms 9 have been fully opened. When the operator removes his foot from the 40 switch 67 the latter opens, thereby breaking the motor circuits, and the springs 52 immediately move the clamps into engagement 45 with the rails, at the same time running the motors 12 backward. When the switch 67 is open the contacts 71 are closed, so that the 50 motors are driven backward on dynamic 55 brake resistances R' .

By the present invention I have provided an extremely efficient rail clamp mechanism which, due to the simplicity of its construction, is relatively inexpensive to manufacture 45 and install. This clamp mechanism insures the clamping of the rails in case one of the cables should happen to break, for the reason that the cables are employed for opening the 50 clamps and springs are employed for closing them. By reason of the toggle arrangement between the springs and the clamp levers, the springs are enabled to exert a powerful 55 closing force upon the clamp levers. Furthermore, the provision of a pair of 60 springs for each clamp connected to the clamp levers through an equalizer and a toggle mechanism, renders it unnecessary to employ 65 particularly heavy springs. It will be noted that the toggle arrangement is such that its mechanical advantage with respect to rail clamping increases as the jaw moves 70 toward the rail. This is highly desirable 75 because the spring means employed for closing the jaws inherently provides a decreas-

ing force. By combining the spring, which is a source of power in decreasing value, with the toggle, which provides an increase in mechanical advantage, the proper clamping action is assured. The arrangement of toggle and spring so that the mechanical advantage of the toggle varies inversely with the power of the spring is also important on the jaw opening step. Once the clamping jaw is clear of the rail, it is desired to do as little work as possible in order to maintain the jaws in open position. Considering the toggle from this point of view it will be apparent that the toggle provides means whereby a decreasingly small force is required for 70 opening the jaws. This means of course that less effort will be expended in maintaining the jaws open so that the toggle when combined with the spring in a manner herein provided is of decided importance whether the jaws are being opened or closed. By connecting the limit switches of the clamp mechanisms for the two legs of the bridge in series in the circuit of the controller for the bridge traversing motor, it is not possible to 80 operate the bridge until both of these clamp mechanisms have been opened.

While I have shown and described a preferred embodiment of my invention, it will be understood that the invention is not 85 limited to this precise embodiment as it may be otherwise embodied within the scope of the appended claims without departing from the spirit thereof.

I claim:

1. In a rail clamp mechanism, a pair of 100 clamp levers adapted to grip the opposite sides of a rail, toggle means connected to said levers and including bell crank means, an equalizer connected to said bell crank 105 means, and a pair of springs connected to said equalizer for rocking said levers into engagement with the rail, substantially as described.

2. In a rail clamp mechanism, a pair of 110 clamp levers adapted to grip the opposite sides of a rail, toggle means connected to said levers, means for actuating said toggle means to rock said levers into engagement with the rail, a sheave journaled on each lever, a drum, 115 a cable connecting said drum with said sheaves, and means for rotating said drum to rock said levers out of engagement with the rail, substantially as described.

3. In a rail clamp mechanism, two pairs of 120 clamp levers adapted to grip a rail at spaced points, and separate toggle means operatively connected to each pair of levers, spring 125 means associated with each toggle means for applying the rail-gripping force to the clamp levers, a drum, cable means connecting the drum with the two pairs of clamp levers, and means for rotating said drum to rock said clamp levers out of engagement with the rail and put said spring means under tension, the 130

toggle means being so arranged that the mechanical advantage of the toggle varies inversely with the power of the spring, substantially as described.

4. In a rail clamp mechanism, a pair of clamp levers adapted to grip the opposite sides of a rail, a bell-crank lever pivoted to one of said clamp levers, a link connecting one arm of said bell-crank lever with the other clamp lever and constituting with said arm a toggle, and spring means connected to the other arm of said bell-crank lever for applying the rail-gripping force to said clamp levers, substantially as described.
5. In a rail clamp mechanism, a pair of clamp levers adapted to grip the opposite sides of a rail, a bell-crank lever pivoted to one of said clamp levers, a link connecting one arm of said bell-crank lever with the other clamp lever and constituting with said arm a toggle, spring means connected to the other arm of said bell-crank lever for applying the rail-gripping force to said clamp levers, a sheave journaled on the upper end of each clamp lever, a drum, a cable connected at one end to the drum and at the other end to the upper end of one of said clamp levers and passing around said sheaves, and means for rotating said drum to rock said clamp levers out of engagement with the rail and place said spring means under tension and for holding said drum in said position, substantially as described.
6. In a rail clamp mechanism, a pair of vertically extending clamp levers pivoted adjacent their lower ends and having gripping jaws at said lower ends adapted to grip the opposite sides of a rail, one of said clamp levers being pivoted adjacent its upper end and having a bell-crank lever pivoted thereto adjacent said upper end, a link connecting one arm of said bell-crank lever with the other clamp lever and constituting with said arm a toggle, and spring means connected to the other arm of said bell-crank lever for applying the rail-gripping force to said clamp levers, substantially as described.
7. In a rail clamp mechanism, a pair of clamp levers adapted to grip the opposite sides of a rail, toggle means connected to said levers, an equalizer connected to said toggle means, and a pair of springs connected to said equalizer for rocking said levers into engagement with the rail, substantially as described.
8. In a rail clamp mechanism for traveling structures, a pair of clamp levers adapted to grip the opposite sides of a rail, spring means for applying the full effective rail gripping force to said levers independently of any movement of said structure along the rail, means for multiplying the power applied by the spring means to the levers, and means for rocking said levers out of engagement with the rail, said means comprising a

drum, a sheave journaled on each lever and a cable connecting said drum with said sheaves, substantially as described.

9. A rail clamp, comprising a movable clamp jaw, a toggle operatively connected thereto, a spring tending to operate the toggle and thus move the clamp jaw against the rail, and opening means for operating the toggle in a reverse direction to clear the clamp jaw of the rail, the toggle and the opening means being so arranged that the force required for opposing the spring and holding the clamp jaw in open position decreases after the jaw is opened, substantially as described.

10. A rail clamp mechanism, comprising clamping jaws, springs for setting the clamping jaws, a connection between the springs and the jaws, and means for positively limiting the range of effective action of the springs on the connection and holding the springs under load, substantially as described.

11. A rail clamp mechanism, comprising clamping jaws, springs for setting the clamping jaws, a connection between the springs and the jaws, and means for holding the springs under load to permit adjustment of the connection, substantially as described.

12. A rail clamp mechanism, comprising a clamp jaw, a spring for setting the clamping jaw, a member movable by the spring and adapted to transmit force supplied by said spring, a connection between the member and the clamping jaw, and means for limiting the movement of said member so as to maintain the spring under load, substantially as described.

13. A rail clamp comprising a clamping jaw, a spring for actuating the jaw, a frame member against which the spring is biased, the frame member having an opening therein, a rod extending through the opening, and a stop on the rod effective for engaging that portion of the frame member adjacent the opening and limiting the movement of the spring.

14. A rail clamp comprising a clamp, a plurality of springs for actuating the same, a frame member against which the springs are biased, the frame member having openings therein, an equalizing linkage having portions extending through the openings and making operative connections with the springs, and stops engaged by those portions of the frame member adjacent the openings for limiting the movements of the springs.

In testimony whereof I have hereunto set my hand.

BERNARD H. KERSTING.
